DESIGN FOR A TELEPHONE HOLDER

Raymond B. Bianchi, Chicago, Ill., assignor of one-half to Ned E. Cahen, Chicago, Ill.

Application May 18, 1946, Serial No. 129,842

Term of patent 3½ years

(Cl. D26—14)

To all whom it may concern:

Be it known that I, Raymond B. Bianchi, a citizen of the United States and resident of the city of Chicago, county of Cook, and State of Illinois, have invented a new, original, and ornamental Design for a Telephone Holder, of which the following is a specification, reference being had to the accompanying drawing, forming a part thereof, in which a perspective view of a telephone holder, showing my new design, is illustrated.

I claim:

The ornamental design for a telephone holder, substantially as shown.

RAYMOND B. BIANCHI.
